UNITED STATES PATENT OFFICE.

HUGO DAHMS, OF BERLIN, GERMANY.

MEANS FOR ATTACHING STOCKINGS, SOCKS, OR THE LIKE TO SUSPENDERS.

Application filed April 16, 1923. Serial No. 632,471.

To all whom it may concern:

Be it known that I, HUGO DAHMS, a subject of the Republic of Germany, and resident of Berlin, Germany, have invented a new and useful Means for Attaching Stockings, Socks, or the like to Suspenders (for which I have filed an application in Germany, No. 103,823, X/3^a, March 2, 1922), of which the following is a specification.

10 The present invention relates to stocking or sock suspenders and has for its object to provide improved means for attaching the stocking or sock to the suspender, which will be particularly simple and easily manipulated and which will not be bulky.

The attaching means according to the present invention consists of a triangular stirrup with an extension at its apex or lowest point forming a smaller triangle or the like, the stocking being drawn through the larger triangle and laid over the base of the smaller triangle. The pull on the suspender causes the fabric to cling tightly round the extension and to press it firmly into the apex of the triangle, thereby holding the stocking securely. The stocking is readily released after the stirrup has been turned upwards.

The accompanying drawing represents a constructional form of the invention,

20 Figures 1 and 2 showing the attaching means in the course of construction and in the finished state,

25 Figure 3 the manner in which the attaching means is attached to the suspender and

30 Figure 4 a side view of Figure 3, partly in section.

The attaching means consists of a wire structure in the form of a triangular stirrup *b* and a part *e*, which is also triangular in shape and forms an extension at the bottom angle of the triangle. The wire is provided in a known manner with a covering of rubber, textile fabric or the like, which acts as a protection for the stocking and helps the stocking fabric to adhere. After the rubber tube or the like has been drawn over the wire the extension *e* is twisted through 180° relatively to the stirrup *b*, so that the point of connection between these two parts 45 is closed and the stocking is prevented from slipping through.

The ends *s* of the wire are surrounded in

a known manner by a sleeve *m*. The elastic suspender is attached to this sleeve by being sewn round it.

The inclined limbs of the upper, larger triangular part *b* force the stocking through the pull of the suspender into the bottom angle of the said part and consequently to embrace the lower, smaller triangular part *e* more and more towards its apex, thus preventing the stocking from becoming detached unintentionally.

Having now particularly described and ascertained the nature of my said invention and in what manner the same is to be performed, I declare that what I claim is:—

1. Means for attaching stockings, socks and the like to suspenders, comprising a triangular wire stirrup having the apex directed downwardly, and a smaller triangular wire member having its apex connected with the apex of the stirrup, the portion of the wire constituting the apices of the stirrup and triangular member being twisted together to prevent separation of the sides of the stirrup and triangular member, the stocking being adapted to be drawn through and compressed in the apex of the stirrup and to be laid over the base of the smaller triangular member.

2. Means for attaching stockings, socks and the like to suspenders, comprising a triangular wire stirrup having the apex directed downwardly, and a smaller triangular wire member having its apex connected with the apex of the stirrup, the portion of the wire constituting the apices of the stirrup and triangular member being twisted together to prevent separation of the sides of the stirrup and triangular member, the stocking being adapted to be drawn through and compressed in the apex of the stirrup and to be laid over the base of the smaller triangular member, and a tubular covering applied to the wire constituting the stirrup and smaller triangular member.

In testimony whereof I have signed my name to this specification.

HUGO DAHMS.

Witnesses:

HANS NEIMAN,

KARL MARBERRY.
